(57) **CLAIM**

The ornamental design for a light fixture, as shown and described.

DESCRIPTION

FIG. 1 is a perspective view of a top, front, and right side of an ornamental design for a light fixture;

FIG. 2 is a front elevational view of FIG. 1;

FIG. 3 is a rear elevational view of the light fixture of FIG. 1;

FIG. 4 is a right side elevational view of the light fixture of FIG. 1;

FIG. 5 is a left side elevational view of the light fixture of FIG. 1; and,

FIG. 6 is a top plan view of the light fixture of FIG. 1. The dash-dash-dash lines are included for the purpose of illustrating portions of the light fixture that form no part of the claimed design. The dash-dot-dash broken lines are included for the purpose of illustrating boundary lines and form no part of the claimed design.

1 Claim, 6 Drawing Sheets
